HOLLIS W. MOYSE, OF NEW BRUNSWICK, NEW JERSEY, ASSIGNOR TO DU PONT FILM MANUFACTURING CORPORATION, OF WILMINGTON, DELAWARE, A CORPORATION OF DELAWARE

MULTIPACK NEGATIVE SYSTEM

Application filed June 20, 1930. Serial No. 462,471.

This invention relates to color separation negatives and more particularly to an improved multi-pack negative system.

Many methods have been devised for making color separation negatives for use in color photography. Many of these methods require special cameras with filter attachments, prisms, reflectors, etc. Perhaps the easiest method for making color separation negatives has been the bi-pack and tri-pack arrangements wherein two or three negatives are stacked upon each other and loaded in the ordinary cameras. This system of color separation is, however, subject to certain disadvantages one of which is the lack of sharpness of the image produced on the rear emulsion in the bi-pack negative system and on the middle and rear emulsions in the tri-pack negative system.

This invention has as an object the production of a multi-pack negative system having improved means associated therewith capable of minimizing the tendency to lack of sharpness in the rear film or films. A further object is the production of a multi-pack negative system in which the aforesaid means is applied as a coating to the surface of a rear emulsion.

These objects are accomplished by the following invention in which a layer or film of transparent colloid is positioned between the emulsion of a rear negative and the light filtering means of a front negative, the colloid layer being coated on the surface of an emulsion, preferably on the surface of the rear emulsion.

In the drawing:

Fig. 1 is a section through one form of bi-pack system illustrating my improvement associated therewith and Fig. 2 shows my improvement associated with another form of bi-pack film.

In the form shown in Fig. 1, the front film or negative is composed of a film base 1 carrying an orthochromatic emulsion 2 sensitive to blue and green light rays. The numeral 3 is a color screen composed of a coating of dyed or stained colloid which filters out all but the red rays passing to the panchromatic emulsion 5 on the film base 6. A coating 4

of transparent undyed colloid is applied to the surface of the rear emulsion 5.

The colloid coatings 3 and 4 may be made from solutions of colloids such as gelatin, agar, casein, etc., which are coated on the emulsion layer in a separate operation during manufacture in the same manner that the emulsion is coated.

The sharpness of the image on a rear negative of multi-pack systems is largely dependent upon the degree of contact the emulsion surface of the rear film makes with the emulsion surface of the front film. A colloid layer, such as gelatin, as will be apparent, will make better contact with an emulsion surface than one emulsion will make with another. The light scattering effect of the emulsion surfaces is, however, the main reason for the lack of sharpness of the image on the rear film. A negative emulsion surface is granular or discontinuous and has a distinct matt appearance due to the separate particles of silver bromide crystals. The light is scattered and diffused by such a surface, the effect increasing with increasing separation of the emulsion surfaces. A colloid layer, on the other hand, has a smooth continuous surface which together with the better contact with the emulsion, permits the light rays to pass with less distortion from one emulsion to the other.

The light filtering screen consisting of a dyed colloid coated on to the front emulsion is claimed in the copending application of Virgil B. Sease, filed June 19, 1930 Ser. No. 462,197 and no claims to this combination per se are made herein. This dyed layer of colloid, as disclosed in the aforesaid application tends to prevent the undesirable effects referred to above. I have discovered, however, that a layer of transparent undyed colloid coated on the surface of a rear emulsion makes possible the formation of a still sharper image on the rear emulsion than does the dyed colloid alone. When a single layer of colloid is used, as in the application referred to, the layer can be applied as a coating to only one emulsion and the contact of the layer with the adjacent emulsion is, of course not so intimate. In the present invention wherein the colloid is applied as a coating to both

emulsions, the contact between the adjacent colloid surfaces is better than the contact one surface of a single coating makes with emulsion surface adjacent the one to which the 5 coating is applied. The advantages gained from the better contact more than offset any tendency to get slight diffusion on the rear film due to the separation caused by the colloid layers.

10 In the preferred form of the invention as described above, my improvement is associated with a multi-pack negative system in which a front emulsion has applied thereto a layer of dyed colloid. The present invention 15 is, however, applicable to multi-pack negative systems in which the light filtering means is associated with a front emulsion in a manner different than that previously referred to.

20 In Fig. 2 a coating of dyed or stained emulsion 2' is applied to the film base 1' and the coating of clear undyed colloid 4' is coated on to the surface of the rear or second emulsion 5' carried by the base 6' as in Fig. 1. As 25 previously noted, the sharpness of the image on the rear emulsion is dependent upon the closeness of contact of the emulsions, and, as will be apparent the surface of the dyed emulsion 2' will make better contact with the 30 smooth surface of the colloid layer 4' than it would with the surface of emulsion 5'. The term "light filtering means" as used herein comprises, therefore, the dye or stain in the emulsion itself as well as the layer of 35 dyed colloid illustrated in Fig. 1.

While I have found a coating of a colloid to be the most effective as a medium for carrying out the invention, it will be apparent that the invention is not restricted to 40 this class of materials but may be practiced by using coatings of materials having substantially the same characteristics as colloid coatings.

When the clear colloid layer 4 or 4' is 45 coated on the emulsion surface, a fusion takes place and since there is no difference in the index of refraction between the colloid of the emulsion and the colloid of the layer it becomes impossible to detect any surface at 50 the original face of the emulsion. The clear colloid layer 4' could if desired, be coated onto the surface of the dyed emulsion 2'.

The fuzzy rear image resulting from the 55 diffusion of light from the matt surfaces of the emulsion layers has been a serious defect in the known bi-pack negative systems. These defects are practically eliminated or minimized by means of the colloid layer or 60 layers as herein disclosed.

As many apparently widely different embodiments of this invention may be made without departing from the spirit and scope thereof, it is to be understood that I do not limit myself to the specific embodiments

thereof, except as defined in the appended claims.

I claim:

1. In a multi-pack negative system; a front light sensitive emulsion having coalescently 70 coated thereon a relatively thin, transparent, water-permeable, dyed colloid, to minimize the scattering of light, and a rear emulsion having a like coating thereon that is undyed.

2. In a multi-pack negative system, a front emulsion having light filtering means associated therewith and a rear emulsion having a smooth surfaced coating of transparent, undyed, water-permeable colloid, coalescently united with surface of said rear emulsion.

3. In a multi-pack negative system comprising a plurality of light-sensitive emulsions; a relatively thin, transparent, water-permeable, smooth surfaced colloid coating, coalescently united with the surface of each of the said emulsions.

In testimony whereof, I affix my signature.
HOLLIS W. MOYSE.
